ATTACHING SOCKET FOR SHOE CLEATS

Hugh D. Driscoll, Tulsa, Okla.

Application October 9, 1935, Serial No. 44,293

8 Claims. (Cl. 36—66)

This invention relates to attaching sockets for shoe cleats of that general class shown and described in United States Letters Patent issued to me on the 3rd day of December, 1935 under No. 2,022,655, the present invention being an improvement thereon.

The object of the invention is to provide a shoe sole socket of simple and inexpensive construction capable of being readily attached to the outer lift of a shoe sole, either during the manufacture of the shoe or subsequent thereto and which will provide a secure anchorage for the opposite ends of a shoe cleat and effectually prevent accidental displacement of said shoe cleat when walking, playing golf, or under other conditions of service.

A further object of the invention is to provide a shoe sole socket, the construction of which is such as positively to clamp the opposite faces of the outer shoe lift and thus prevent the socket from working loose or being forced upwardly and embedded within the adjacent surface of the inner shoe lift.

A further object is to provide a shoe sole socket including a face plate having a recess formed therein communicating with a slot or socket in the shoe sole and provided with spaced attaching spurs adapted to extend through the socket or slot and engage the grooved face of a clamping plate.

A further object is to form the opposite walls of the slot or socket in the shoe sole with flat faces against which the attaching spurs bear so as to prevent accidental rotation of the face plate.

A still further object of the invention is generally to improve the construction of the socket whereby the use of attaching nails, screws and similar fastening devices is entirely dispensed with.

In the accompanying drawing forming a part of this specification and in which similar numerals of reference indicate corresponding parts in all the figures of the drawing,—

Figure 1 is a bottom plan view of a shoe provided with an attaching socket constructed in accordance with the present invention, the cleat or anti-skid tread surface being indicated in dot and dash lines.

Figure 2 is a vertical sectional view taken on the line 2—2 of Figure 1.

Figure 3 is a transverse sectional view taken on the line 3—3 of Figure 1.

Figure 4 is a detail top plan view looking at the inner face of the outer lift and showing how

the terminals of the attaching spurs engage the clamping plate.

Figure 5 is a group perspective view with the parts comprising the socket separated.

Figure 6 is a group perspective view illustrating a modified form of the invention.

The improved shoe sole socket forming the subject-matter of the present invention is principally designed for detachably securing a shoe cleat or other anti-skid tread surface in position 10 on the outer lift of the sole of a shoe, and by way of illustration is shown in connection with a shoe of conventional construction, in which 5 designates the upper, 6 the outer sole or lift, and 7 the inner sole, the cleat or anti-skid tread surface 15 being indicated in dot and dash lines at 8. The cleat 8 is of the construction shown in my patent previously referred to and embodies a plurality of pivotally connected links, there being a headed pin 9 secured to each end of the cleat and co-acting with a shoe sole socket for detachably securing the cleat in position on the shoe.

The shoe sole socket comprises an outer face plate 10 formed of metal or other suitable material and preferably circular in shape, as shown, 25 the central portion of the face plate being provided with a substantially elliptical-shaped opening 11 which communicates with a slot or socket 12 formed in the outer lift 6 of the shoe. The slot or socket 12 extends entirely through the outer 30 shoe lift 6 and the width of said slot or socket is preferably less than the diameter of the face plate 10 so that when the face plate is positioned on the outer surface of the lift 6, said face plate will entirely cover the socket, as best shown in 35 Figure 2 of the drawing. Secured to or formed integral with the face plate 10 are upstanding attaching spurs 13 adapted to extend through the slot or socket 12 for engagement with an inner or clamping plate 14. It will here be noted 40 that the slot 12 is narrower at its ends than at the center thereof and that the end walls at the narrow portion are flat or straight but of approximately the same width as the attaching spurs to form shoulders or abutments 15 for 45 engagement with said spurs so that when the face plate is positioned on the shoe sole, the spurs 13, by engagement with said flat walls or abutments, will prevent accidental rotation of said face plate. The inner or clamping plate 14 is 50 preferably in the form of a flat metal disc of a diameter equal to or approximately equal to that of the face plate 10 and at opposite sides of the disc or clamping plate 14 the metal is cut away 55 to form locking notches 15' adapted to receive

the adjacent ends of the attaching spurs 13. The metal constituting the disc 14 is stamped or otherwise depressed between the locking notches to form a transverse seating groove 16 adapted 5 to receive the pointed terminals 17 of the attaching spurs so that when said attaching spurs are bent laterally they will seat within the groove 16 and thus present a perfectly flat flush surface for 10 contact with the adjacent surface of the inner sole or lift 7, as best shown in Figure 2 of the drawing.

In applying the improved socket to a shoe sole, the outer sole or lift is stamped, punched, or otherwise formed with the slot or socket 12, after 15 which the face plate 10 is positioned on the outer surface of the lift 6 with the attaching spurs 13 extending through the slot 12 and in engagement with the flat walls or abutments 15 thereof. The clamping plate 14 having been previously 20 positioned on the inner face of the lift 6, the terminals of the attaching spurs are bent downwardly within the seating groove 16 thereby firmly clamping the parts together and preventing accidental displacement of the device. It is preferred to slightly moisten the leather of which 25 the lift 6 is formed prior to the application of the socket thereto as by doing so the face plate and clamping plate will automatically seat themselves in the soft leather so that said plates will 30 be disposed substantially flush with the respective faces of the shoe lift. It will thus be seen that the walls or abutments 15 of the slot or socket 12 serve to prevent accidental rotation 35 of the face plate while the attaching spurs 13 by engagement with the clamping plate 14 serve to securely clamp the device in position on the shoe sole. As the device is positively clamped on the shoe sole, it follows that liability of the face plate being forced upwardly or causing the 40 clamping plate to become embedded in the inner sole is prevented and such movement is further prevented owing to the broad bearing surface the clamping plate presents to the inner sole.

In applying the cleat to the socket it is merely 45 necessary to turn the cleat at right angles to shoe until the headed pin 9 of the cleat registers with the recess 11 in the face plate when the head will readily pass through the recess 11 into the socket 12. By then giving the cleat a quarter turn, that is to say, moving the cleat to the 50 position shown in Figure 1 of the drawing, the headed pin 9 will engage the walls of the face plate around the recess 11 therein and detachably hold the cleat in position on a shoe sole, 55 as set forth in my prior patent.

While it is preferred to make the slot or socket 12 of the shape shown in Figure 5 of the drawing, it will, of course, be understood that this slot or socket may be of any other desired configuration so long as the flat end walls or abutments 15 are present and the slot or socket is of less width than the diameter of the face plate so that the face plate when positioned on the shoe sole will extend beyond the walls of the 60 socket. A shoe socket constructed in accordance with the present invention may be applied with equally good results to a shoe sole during the manufacture of the shoe or when half soling a shoe without the employment of nails, screws 65 and similar fastening devices, the stitching used for securing the outer lift of the sole to the inner lift serving to hold the clamping plate against the inner sole, as will be readily understood. It will, furthermore, be noted that the 70 plate or disc 14 not only forms a clamping mem-

ber but also constitutes a closure for the inner end of the slot or socket 12, so as to prevent moisture, dirt and foreign matter which might possibly enter the socket through the opening in the face plate when the cleat is removed, from finding lodgment between the inner and outer lifts of the shoe sole. 5

In Figure 6 of the drawing, I have shown the face plate provided with three attaching spurs 13' which fit in countersunk seats 18 extending inwardly from the circumferential edge of the clamping plate. It will, of course, be understood that any desired number of such spurs may be employed and that said spurs may be of any desired width and the terminals thereof pointed 15 or blunt as desired without departing from the spirit of the invention. 10

Having thus described the invention, what is claimed as new is:

1. The combination with a shoe sole having a 20 socket therein, of a face plate bearing flat against the outer surface of the shoe sole and provided with a recess communicating with the socket, a solid imperforate clamping plate disposed substantially flush with and engaging the inner face 25 of the shoe sole, and attaching spurs carried by the face plate and adapted to extend through the shoe sole and bear against the clamping plate for clamping the shoe sole between said plates. 30

2. The combination with a shoe sole having a 35 socket therein, of a face plate countersunk in the outer surface of the shoe sole and provided with a recess communicating with the socket, a solid imperforate clamping plate disposed substantially flush with the inner face of the shoe sole and having oppositely arranged locking notches formed therein, and attaching spurs carried by the face plate and adapted to engage the adjacent walls of said socket and said notches 40 with their terminals bent laterally in engagement with the upper surface of the clamping plate for clamping the shoe sole between said plates, said clamping plate forming a closure for one end of the socket. 45

3. The combination with a shoe sole having a 50 socket therein, of a face plate bearing flat against the outer surface of the shoe sole and provided with a recess communicating with the socket, a clamping plate disposed substantially flush with 55 and engaging the inner surface of the shoe sole, said clamping plate being provided with a transverse seating groove terminating in locking notches, and attaching spurs extending upwardly from the face plate and bearing against the adjacent walls of said socket and said notches with their terminals bent downwardly within the seating groove.

4. The combination with a shoe sole having a 60 socket therein provided with two straight walls, of a face plate bearing flat against the outer surface of the shoe sole and provided with a recess communicating with the socket, a solid 65 clamping plate disposed substantially flush with and bearing against the inner surface of the shoe sole, and attaching members carried by the face plate and bearing against the straight walls of the socket with their terminals bent downwardly in engagement with the clamping plate. 70

5. The combination with a shoe sole having an 75 elongated socket therein, there being vertical walls at the opposite ends of the major axis of the socket and constituting abutments, a solid imperforate clamping plate disposed substan-

tially flush with and engaging the inner surface of the shoe sole and provided with a transversely disposed depressed seating groove, the opposite sides of the clamping plate at said seating groove being cut away to form locking notches, a flat face plate countersunk in the outer surface of the shoe sole and having a recess therein communicating with the socket, and attaching members projecting upwardly from the face plate and bearing against the abutments of the socket and the adjacent walls of the locking notches with their terminals bent downwardly in engagement with the seating groove whereby said terminals will be disposed flush with the upper surface of the clamping plate.

6. An attaching socket comprising a face plate having a recess therein and a solid continuous clamping plate provided with seating grooves, said plates being adapted to bear flat against the opposite sides of a slotted member, and attaching spurs carried by the face plate and adapted to extend through said member with the seating grooves, said clamping plate extending entirely across the top of the slot in said member and forming a closure for said slot.

7. An attaching socket comprising a face plate having a recess therein and a solid imperforate clamping plate provided with oppositely disposed

locking notches connected by a transverse seating groove, said face plate and clamping plate being adapted to bear flat against the opposite sides of a slotted member, and upstanding attaching spurs formed integral with the face plate and adapted to bear against the adjacent walls of the slot in said member and against the locking notches with their terminals bent laterally within the seating groove, said clamping plate serving to completely close that end of the slot opposite the recess in the face plate.

8. The combination with a shoe sole having a socket extending entirely therethrough and reduced in width at its opposite ends to form terminal abutments, a clamping plate disposed substantially flush with the inner face of the shoe sole and forming a closure for the central and reduced portions of the socket and provided with countersunk seats and a face plate having a recess therein communicating with the lower side of the socket and provided with a plurality of peripheral attaching spurs adapted to extend through the reduced portions of the socket and engage the seats in the clamping plate with the intermediate portions of the attaching spurs bearing against said abutments.
